UNITED STATES PATENT OFFICE.

MATTHEW BENTLEY AND JOHN BENTLEY, OF DUDSWELL, QUEBEC, CANADA.

QUARRYING PLUG OR WEDGE.

SPECIFICATION forming part of Letters Patent No. 374,574, dated December 13, 1887.

Application filed May 12, 1887. Serial No. 237,990. (No model.)

To all whom it may concern:

Be it known that we, MATTHEW BENTLEY and JOHN BENTLEY, citizens of Canada, residing at Dudswell, in the county of Wolfe and 5 Province of Quebec, Canada, have invented an Improved Quarrying-Plug; and we do hereby declare the following to be a full, clear, and exact description of the same.

Our invention relates to improvements in 10 plugs used as wedges for dividing large stones in quarries; and the objects of our invention are, first, to lessen the cost of quarrying implements and to secure a large advantage from the manual labor expended in parting or blocking-out stone blocks from the layers or strata formations. We attain these objects by means 15 of the plug shown in the accompanying drawings, which illustrate our invention, and in which—

20 Figure 1 is a side view, and Fig. 2 a transverse section on line x x , Fig. 1, of our improved plug.

The present practice in quarrying is to use 25 plugs in connection with iron or steel feather-strips, which are placed in the hole previously drilled in the rock, and then the plug is driven down between them, which has the effect of splitting the rock at this point. When it is desired to break off a straight face of consider- 30 able length, a number of holes are drilled in a straight line and plugs driven into them, which has the effect of splitting the rock in the direction of the line of holes.

For the proper working of these plugs in 35 the rock there should be no pressure against those sides of the drill-hole which are in the

line of fracture, the whole of the bursting force of the plug being in a direction at a right angle from the line of fracture. To this end the feather strips above mentioned are placed on 40 the outer and inner sides of the hole, so that the plug expands only in that direction. We attain this object without the use of feather-strips by means of our improved plug A, which is tapered on all sides toward one end, but has 45 two flat sides B, as shown in Fig. 2, extending from the point or smaller end up to near its larger end. This plug is placed in the drill-hole, so that its flat sides will face the direction of fracture c c , and its resistance will be 50 only from points at right angles from the line of fracture. From this it will be seen that by our improvement the labor of driving the plug is very much reduced, as is also the cost of 55 quarrying implements, by dispensing with the feather-strips.

Having thus described our invention, we claim as ours and desire to secure by Letters Patent—

A quarry-plug having rounded and flat- 60 tened sides, respectively oppositely arranged, whereby the use of feather-strips is avoided, substantially as described.

Signed at Sherbrooke this 7th day of May, 1887.

MATTHEW BENTLEY.
JOHN BENTLEY.
